GLARE SHIELD

Goldie Hoffman, 250 S. 17th St.,
Philadelphia, Pa. 19103

Filed Dec. 22, 1965, Ser. No. 275

Term of patent 3½ years

(Cl. D57—1)

The headbands are omitted in FIGURE 1 and shown broken away in FIGURE 7 for convenience of illustration.

The dominant features of my design reside in the portions shown in full lines.

I claim:

The ornamental design for a glare shield, substantially as shown and described.
